PATIENT AND BEDDING REMOVER

Robert M. Russell, Woodhaven, N. Y.

Application August 21, 1942, Serial No. 455,599

3 Claims. (Cl. 5—89)

This invention relates to patient and bedding removers, and more particularly to a device in the nature of a stretcher which is adapted to be permanently kept under the mattress of a hospital bed to enable the attendants to evacuate the patient or to move the patient from one bed to another without injury.

While my device may be used on any bed, it is particularly adapted to hospital beds, and provision has been made to allow for the raising and lowering of the head and foot members.

In the accompanying drawings:

Fig. 1 is a plan view of an embodiment of my invention;

Fig. 2 is a plan view showing the carrying members as they are disposed when not in use;

Fig. 3 is an end view showing the manner in which the carrying members are adapted to break to conform with standard hospital beds;

Fig. 4 is a cross sectional view taken on the line 4—4 of Fig. 1;

Fig. 5 is an enlarged detail view showing the construction of the supporting members;

Fig. 6 is an enlarged detail view in section showing the manner of fastening the members together;

Fig. 7 is a sectional view showing the joint to allow the carrying members to bend; and

Fig. 8 is a plan view of said joint.

Referring more particularly to the drawings, my device 10 consists of two carrying members or bearers 11 and 12. These members may be made of any suitable material, but for practical purposes, tubular steel is most suitable for reasons of strength, sanitation and safety. The members 11 and 12 are provided with joints 14, 15, 16 and 17. The joints 14 and 16 are approximately 27" from the end of the carrying members, while the joints 15 and 17 are approximately 21" from the opposite end of the carrying members. These joints are set to coincide with the hinged portion of a hospital bed so that when the device is placed under the mattress of a hospital bed, it will be possible to raise and lower the head and foot portions. The joints 14 and 16 coincide with the head portion, while the joints 15 and 17 coincide with the foot portions.

While any suitable form of joint may be used, I have found the joint shown in Figs. 7 and 8 to be adequate. This joint is simply formed by placing the plug 18 within the tubular end 19 and fastening it by a rivet 20. Plug 18 has a tongue 21 which is adapted to lie within the groove 22 in the corresponding section of the carrying member. A rivet 23 extends through both members to

form a pintle for the hinge. Attached to the pintle by means of a link or chain 24, is a pin 25 which is adapted to engage the openings 26 in the tongue, and 27 in the groove member to lock the hinge against movement. Fastened to the carrying members 11 and 12 by means of rivet 30 passing therethrough, are linkage chains 31. These chains engage a Z-shaped spring member 32 which, in turn, is fastened by the links 33 to the plate or supporting member 34. A spacing bar 35 may be placed between the chain 31 to avoid the possibility of entanglement. Each group of interconnected parts 31—38 constitutes a transverse bearer, there being six of such bearers in the present instance, although any number may be used.

While any number of units may be used to make up the supporting structure between the carrying members, I have found that two plates 34, each fastened to the carrying member, as heretofore described, and fastened to each other by the links 37 and a Z-shaped spring member 38, is satisfactory.

In use, the entire device is placed between the spring and mattress of a hospital bed, and the carrying members 11 and 12 slid under the edge of the mattress, in the position shown in Fig. 2. This is possible, due to the flexibility of the chain 31. Since all of the parts are flat, except the carrying members, the bed will not be disturbed by the presence of my device.

If it is desired to raise the head portion of the bed, pins 25 can be removed and the head portion 40 raised, as indicated in Fig. 3. The foot portions 41 may be similarly raised. In the event of an air raid or fire, the patient may be evacuated without removing him from his mattress or disturbing his bed in any way. It is only necessary for two people to grasp the carrying members 11 and 12 at either end and to lift the mattress, bedding, patient and all from the bed and thus move the entire load without disturbing the patient at all.

While my device is particularly adapted for emergency evacuation or movements, it is equally applicable for normal movements of patients from one bed to another whenever it is desired not to move the patient from his mattress.

While I have shown my device as adapted to be used with a conventional hospital bed, it will be appreciated that hinges may be eliminated when the device is used with an ordinary bed. It will also be appreciated that the hinges may have a conventional locking means, such as a sleeve, substituted for the pin.

I claim:

1. A patient and bedding remover adapted to be positioned between the mattress and spring of a conventional hospital bed having hinged foot and head sections, said remover comprising a pair of rigid carrying members, hinges in said rigid carrying members adjacent the hinges of the foot and head sections of the conventional hospital bed, means for locking said hinges against movement, when the sections of said members are in line, and supporting units extending crosswise of said members and connected therewith, each of said units consisting of a flat plate-like members adapted to be positioned under the mattress, flat spring members connecting said flat plate-like members, and flexible means connecting said flat plate-like members to said carrying members.

2. A stretcher of the character described comprising rigid longitudinal bearers arranged in

spaced relation, and non-rigid transverse bearers arranged between and connected with said longitudinal bearers, each of said transverse bearers comprising plates, spring members adjacent the ends of the plates, linkage connecting the spring members with the plates and additional linkage connecting certain of the spring members with the longitudinal bearers.

3. A stretcher of the character to underlie the bedding of a bed for carrying the bedding and the body of a person lying thereon, comprising rigid longitudinal bearers arranged in spaced relation, and supporting units extending crosswise between said bearers and connected therewith, each of said units including flat plates, Z-shape springs and links connecting the springs with the plates so that the plates, springs and links may adjust themselves to the contour of the bedding.
